UNITED STATES PATENT OFFICE.

CARL C. HINKLEY, OF DETROIT, MICHIGAN.

DESIGN FOR AN ENGINE-CASING.

59,843.

Specification for Design.

Patented Nov. 29, 1921.

Application filed November 10, 1919. Serial No. 337,034. Term of patent 14 years.

To all whom it may concern:

Be it known that I, CARL C. HINKLEY, a citizen of the United States of America, residing at Detroit, in the county of Wayne and State of Michigan, have invented an original and ornamental Design for an Engine-Casing, of which the following is a specification, reference being had therein to

the accompanying drawings, forming part thereof, in which

Figures 1 and 2 are elevations respectively of opposite sides of the engine casing.

I claim:

The ornamental design for an engine casing, as shown.

CARL C. HINKLEY.
